(57) **CLAIM**

The ornamental design for a finned hazardous condition detector, as shown and described.

DESCRIPTION

FIG. 1 is a perspective view of an embodiment of a finned hazardous condition detector showing my new design;

FIG. 2 is a top view thereof;

FIG. 3 is a bottom view thereof;

FIG. 4 is side view thereof;

FIG. 5 is a second side view thereof;

FIG. 6 is a third side view thereof; and,

FIG. 7 is a fourth side view thereof.

In the drawings, the broken line showing of oval elements on the top of the design depicts environmental subject matter and forms no part of the claim.
